ROTARY GRINDING AND POLISHING DEVICE

Eugene F. Cook, Kansas City, Mo.

Application May 31, 1929. Serial No. 367,268

8 Claims. (Cl. 51—184.1)

This invention relates to rotary grinding and polishing devices, and more especially to devices of the class named, for operation on the interior walls of cylinders, particularly cylinders of internal combustion motors, and my object is to produce a device in which the grinding elements are rigidly positioned relative to the object operated on, as distinguished from the devices in which such elements apply a yielding pressure, with the consequent possibility of inaccurate grinding. Another object is to produce a grinder which will operate effectively without lubrication of the cutting surfaces, and hence expedite the grinding operation.

15 A further object is to provide means for effecting quick adjustment of the device from its minimum "set" to the maximum "set" permitted by the cylinder to be operated on, and other means for effecting additional expansion of the device 20 as required during the progress of the grinding or polishing operation.

Another object is to provide a construction whereby the honing or abrading elements of the device, because held rigidly, perform their function without vibration and hence avoid the chattering which is common in and impairs the efficiency of operation and accuracy in the grinding operation.

30 Another object is to provide a construction which guards against the possibility of a grinding or polishing element being dislodged through centrifugal action or force, in the event the device is wholly withdrawn while at high speed, from a cylinder.

35 With these objects in view and others, as hereinafter appear, the invention consists in certain novel and useful features of construction and combinations of parts as hereinafter described and claimed; and in order that it may be fully understood, reference is to be had to the accompanying drawing, in which:

Figure 1 is an end view of the appliance with the grinding and polishing elements omitted and the drive shaft in section on the line I—I of Figure 2, the drive shaft being indicated in horizontal view in dotted lines.

45 Figure 2 is a side elevation of the complete device.

50 Figure 3 is a horizontal section on the line III—III of Figure 2.

Figure 4 is a full size fragmentary central section of the device.

55 Figure 5 is a horizontal section on the line V—V of Figure 4.

Figure 6 is a face view of a nut forming an element of the device.

Figure 7 is a view of the outer or upper end of the body portion of the device.

Figure 8 is a fragmentary vertical section of 60 the inner or lower end of the body portion and pinion shaft.

Referring to the drawing in detail, 1 indicates a generally cylindrical body portion having a longitudinal axial bore 2, and a series of projecting pins 3 at the outer or upper end, the pins being arranged circularly and concentrically with respect to the bore 2.

The body portion is provided with cross passages 4 intersecting or opening into the bore 2. 70 There are preferably four of these passages, arranged in pairs spaced apart, and extending in parallel relation, and the passages of each pair are disposed at opposite sides of the axial center of the body portion. There is a similar set of 75 passages 4 which bear the relation to each other and to the bore 2 above explained, but which extend angularly, with respect to the first-named passages, preferably at right angles to the latter.

Rack bars 5, extend through the first-named 80 passages 4, and similar rack bars 6 extend through the other passages 4. The teeth 7 of the rack bars 5 and 6, are faced toward the axis of bore 2, and the opposite ends of the bars of each pair, terminate in teeth or lugs 8 of greater 85 width than the rack teeth, for a purpose which hereinafter appears. Each pair of parallel rack bars lying in the same longitudinal plane, is rigidly connected by a dovetail holder 9, and secured rigidly in each holder is a grinding stone 90 or element 10, there being therefore a pair of parallel grinding elements at opposite sides of the body portion and at opposite sides of the axial center of the body portion.

A pair of guides 11, preferably of non-abrasive material, are dovetailed in similar holders carried by the other pairs of rack bars in corresponding longitudinal planes, which guides are adapted to bear against the wall of a cylinder being trued by the grinding operation, so as to cooperate in centralizing the grinding elements in the cylinder, and also serving as guards against such vibration of the grinding elements against the cylinder as would result in a chattering noise and hence imperfect abrasive action on the cylinder.

A cylindrical nut 12 normally fits against the upper or outer end of the body portion, and is formed with a chamber 13, and a circular series of holes 14, a number of which normally engage the pins 3 of the body portion, and the threaded

bore 15 of the nut is preferably of very coarse pitch, as indicated by Figure 6. Fitting rotatably in the bore 2, is an elongated gear pinion or pinion shaft 15a intermeshed with the rack 5 bars so that when said pinion shaft, as it will be hereinafter termed, is turned in one direction or the other, it will impart outward or inward movement to all of the rack bars, it being noted that when the outward limit of movement 10 of said rack bars is reached, the enlarged teeth or lugs of the rack bars will not mesh with the pinion shaft and hence will arrest the outward movement mentioned. The pinion shaft is of substantially the same length as the body portion 1 including the threaded portion of the nut 12, and the upper portion of said pinion shaft, from a point substantially above the adjacent set of rack bars 5, is spirally threaded as at 16 15 at a pitch corresponding to that of the threaded bore 15 of the nut and engages the same so that longitudinal movement of the pinion shaft through the nut shall effect turning movement of the former. The upper end of the pinion shaft has a threaded bore 17, for a purpose which hereinafter appears.

Secured rigidly in the chamber of the nut is a thrust plate 18, provided centrally with a perforated dome portion 19, and fitting upon the nut and thrust plate around the dome 19, is a 30 spring washer 20. Fitting over and upon the dome portion of the thrust plate and the washer, is a dome shaped wheel or rotatable cap 21 roughened peripherally as at 22 to provide a substantial hand grip for manual rotation of the 35 wheel or cap. Secured rigidly in and depending centrally from the wheel or cap is a bolt 23, said bolt extending down through the dome 19 and engaging the threaded bore 17 of the pinion shaft. The preferred means for fastening the 40 bolt rigidly to the wheel cap is by a cross pin 24, and secured upon the bolt and engaging the under side of the dome 19 is a thrust collar 25.

As thus far described it will be apparent that by grasping the wheel or cap, or the nut 12 or 45 both, and applying an upward pull, the bolt 23, will effect upward movement of the pinion shaft, this action being effected without affecting the position of the rack bars. When the parts have been raised high enough to withdraw the nut 50 from engagement with the pins 3 of the body portion, a proper turning movement is applied to the wheel or cap, and all of the parts mentioned as affected by the lifting action, are likewise turned, and the pinion shaft obviously imparts endwise movement to the rack bars so as to effect expansion of the grinding diameter of 55 the device or contraction thereof, as the case may be. The operation mentioned is for the purpose of quickly expanding the device until the grinding elements are arrested by contacting with the wall of a cylinder in the application of the device for operation on the cylinder.

Assuming that the device in its contracted 60 form has been placed within a cylinder preliminarily to the grinding thereof, and the parts have been manipulated as explained to expand the device, the operator next pushes the cap and the affected parts downward until certain of the holes of the nut 12 are engaged with the pins 3 of the body portion. To apply further 70 pressure or adjustment of the grinding elements on the cylinder, the operator can then impart a slight clockwise turning movement to the cap or wheel, the nut at this time being incapable of 75 rotation by reason of its interlocked relation with

the pins of the body portion. This turning movement of the wheel or cap, because the wheel or cap is bearing downwardly against the dome, effects rotation but not endwise movement of the bolt. The latter therefore, turning in the 80 threaded bore 17, effects endwise movement of the pinion shaft, and the engagement of the coarse threads of the latter with the threaded bore of the nut, effects turning movement of said pinion shaft, and said shaft in turning imparts outward thrust on the rack bars and hence of the grinding elements on the wall of the cylinder. To retract the grinding elements, the cap is turned counter-clockwise about a quarter turn, as that is sufficient to withdraw 90 the grinding elements enough to permit withdrawal from the cylinder.

When the parts have been adjusted to grinding relation within a cylinder as explained, the body portion 1 is rotated by any suitable means, and as customary with devices of this character, the device as a whole is also reciprocated so that it shall cover in its operation, the entire length of the cylinder.

In the construction shown, a shaft 26 driven 100 by a suitable motor, not shown, is provided with a forked end 27, which straddles the wheel and nut 12 and is pivoted at diametrically opposite points as at 28 to a ring 29 surrounding the upper end of the body portion, and at right angles to the pivotal points 28, the ring is equipped with pivot bolts 30 which extend into the body portion, the arrangement being such that the ring and shaft have a universal joint connection with the body portion so that whether the shaft 105 26 stands in axial alignment or not with the body portion, the latter can be properly operated to effect the grinding operation.

After the grinding operation is completed the device can be withdrawn from the cylinder and the grinding elements can be replaced by finer ones to give a smoother finish, and finally polishing elements may be substituted if desired, for the purpose of giving a perfectly clean and smooth 110 finish to the interior of the cylinder. In this connection it is desired to call attention to the fact that to avoid the necessity of exercising particular care in raising the nut from engagement with the pins of the body portion, the lower end of the pinion shaft is provided with 115 a pair of circular grooves 31 and 32 spaced apart a somewhat greater distance than the length of the pins 3. The interior wall of the bore of the body portion is also provided with a complementary groove 33 containing a spring ring 34 120 which normally also engages the groove 31 of the pinion shaft. When the latter is raised with the cap and nut, the spring ring is forced to expand until wholly within groove 33, and as the lower groove 32 of the pinion shaft comes within 125 the plane of the spring 34, the latter snaps into the groove 32, without totally withdrawing from groove 33, and thus offers a yielding resistance to accidental withdrawal of the pinion shaft wholly from the body portion, as might occur if 130 the raising action was too vigorous and careless. It is obvious of course that a pull can be applied which will permit the pinion shaft to be wholly withdrawn from the body portion, as the spring ring 34 will then of course expand completely 135 out of groove 32 in the same manner as described with reference to groove 31.

From the above description it will be apparent that I have produced a cylinder grinding device 140 possessing the features of advantage set forth 145

as desirable in the statement of the objects of the invention, and while I have illustrated and described a desirable embodiment, it is to be understood that various changes of detail construction 5 may be resorted to within the principle of construction and mode of operation involved, and hence within the spirit and scope of the appended claims.

I claim:

10 1. A device of the character described comprising a body portion having an axial bore and two sets of cross passages disposed at different angles across the body portion, and communicating with the said bore, rack bars extending 15 through said cross passages, abrasive elements paralleling and at opposite sides of the body portion and each rigidly supported from a pair of rack bars, a pinion shaft extending rotatably through said bore and intermeshed with all of said 20 rack bars, means for effecting longitudinal movement of the pinion shaft, and means, caused by such movement, to impart rotative adjustment to such shaft.

2. In a device of the character described, a 25 body portion having a longitudinal bore and provided at one end with a circular series of pins disposed concentrically with respect to said bore, metal grinding elements carried by the body portion, a nut interlocked with the pins, a pinion 30 shaft journaled in the body portion and provided with a threaded portion engaging the bore of the nut, and connections for transmitting power from the shaft when turned, to effect inward or outward 35 adjustment of the grinding elements relative to the body portion.

3. The combination of a rotatable body portion, a pinion shaft disposed axially therein, rack bars extending crosswise of the body portion and engaging the pinion shaft, work-engaging devices 40 carried by the rack bars, and means to simultaneously effect longitudinal and turning movement of the pinion shaft to adjust the work-engaging devices outwardly or inwardly relative to the body portion.

45 4. The combination of a body portion, work-engaging elements carried by and at opposite sides of and parallel with the body portion, a shaft journaled in the body portion and adapted to be turned for adjustment of the work-engaging elements, and provided with a threaded bore, a 50 nut detachably interlocked with the body portion and threaded on said shaft, a thrust plate rigid with the nut, a cap resting on the said plate,

and a bolt rigidly depending from the cap through the thrust plate and engaging the threaded bore of the shaft, and provided with a collar bearing against the underside of the thrust plate.

5. The combination of a body portion, work-engaging elements carried by and at opposite sides of and parallel with the body portion, a shaft journaled in the body portion and adapted to be turned for adjustment of the work-engaging elements, and provided with a threaded bore, a nut detachably interlocked with the body portion and threaded on said shaft, a thrust plate rigid with the nut, a cap resting on the said plate, a bolt rigidly depending from the cap through the thrust plate and engaging the threaded bore of the shaft, and provided with a collar bearing against the underside of the thrust plate, and a spring washer interposed between and engaged by the cap and the nut. 80

6. In a device of the character described, a rotatable body portion having a longitudinal bore and cross passages intersecting the bore, work-engaging elements, rack-bars rigid with said elements and engaging the respective cross passages of the body portion, a toothed shaft in the said 100 bore and engaging the rack-bars, a part above the upper end of and interlocked with the body portion, a cap above said part, means whereby rotation of the cap shall effect endwise movement of the shaft, and means whereby the part 105 interlocked with the body portion shall effect rotation of the shaft during the endwise movement thereof. 95

7. In a device of the character described, a rotatable body portion having a longitudinal bore 110 and a top pin paralleling the bore, a part upon the body portion and provided with a hole normally engaging the pin, a shaft in the bore having a threaded engagement with said part, a cap, and a connection between the cap and the shaft 115 adapted, when the cap is moved upward from the body portion, to effect like movement of the shaft and cause the latter to withdraw the said part from engagement with said pin. 115

8. In a rotary grinding a polishing tool, a shaft 120 of gear form in cross-section from one end to an intermediate point in its length, and of spiral grooved form in cross-section from the other end to an intermediate point in its length, and provided also with a threaded bore at the spirally 125 grooved end.
